[57] CLAIM

The ornamental design for a medical sensor for measuring oxygen saturation or the like, as shown and described.

DESCRIPTION

FIG. 1 is a perspective view of a medical sensor for measuring oxygen saturation or the like, showing my new design;

FIG. 2 is a front elevational view of FIG. 1;

FIG. 3 is a top elevational view of FIG. 1;

FIG. 4 is a right elevational view of FIG. 1;

FIG. 5 is a left elevational view of FIG. 1;

FIG. 6 is a back elevational view of FIG. 1;

FIG. 7 is a bottom plan view of FIG. 1;

FIG. 8 is a bottom perspective view of FIG. 1;

FIG. 9 is a perspective view of a second embodiment of a medical sensor for measuring oxygen saturation or the like showing my new design;

FIG. 10 is a front elevational view of FIG. 9;

FIG. 11 is a top plan view of FIG. 9;

FIG. 12 is a right elevational view of FIG. 9;

FIG. 13 is a left elevational view of FIG. 9;

FIG. 14 is a back elevational view of FIG. 9;

FIG. 15 is a bottom plan view of FIG. 9;

FIG. 16 is a perspective view of a third embodiment of a medical sensor for measuring oxygen saturation or the like showing my new design;

FIG. 17 is a front elevational view of FIG. 16;

FIG. 18 is a top plan view of FIG. 16;

FIG. 19 is a right elevational view of FIG. 16;

FIG. 20 is a left elevational view of FIG. 16;

FIG. 21 is a back elevational view of FIG. 16; and,

FIG. 22 is a bottom plan view of FIG. 16.
